[57] CLAIM

The ornamental design for a dispensing container, as shown and described.

DESCRIPTION

FIG. 1 is a perspective view taken from the bottom, front and right side of a dispensing container showing my new design;

FIG. 2 is a perspective view taken from the top, rear and right side thereof and

FIG. 3 is a rear elevational view thereof.
The side not shown is a mirror image of the side shown in FIGS. 1 and 2.

FIG.1

FIG.2

FIG.3
